(57) CLAIM

I claim the ornamental design for a combined cosmetic applicator and dispenser, as shown and described.

DESCRIPTION

FIG. 1 is a front view of the combined cosmetic applicator and dispenser;

FIG. 2 is a rear view thereof;

FIG. 3 is a perspective view thereof;

FIG. 4 is a front view of the combined cosmetic applicator and dispenser;

FIG. 5 is a rear view thereof; and,

FIG. 6 is a perspective view thereof.

The broken lines shown in the drawings illustrate a cap. The broken lines form no part of the claimed design.
